UNITED STATES PATENT OFFICE.

JAMES T. NARBETT, OF RICHMOND, CALIFORNIA.

PAVEMENT MARKER.

Application filed December 28, 1922. Serial No. 609,548.

To all whom it may concern:

Be it known that I, JAMES T. NARBETT, a citizen of the United States, and a resident of Richmond, county of Contra Costa, State of California, have invented a new and useful Pavement Marker, of which the following is a specification.

The present invention relates to improvements in pavement markers and its particular object is to provide a portable means for facilitating the marking of streets, garages, public places and the like for the purpose of providing safety zones, parking places for motor vehicles, stop signals and the like. To paint these marks by the mere use of a hand brush takes considerable time and is impractical since the marks very often have to be drawn across busy streets where the work is interrupted frequently by passing street cars or motor vehicles. My device is designed to provide a convenient portable means for making these marks allowing the whole operation to be performed by simply pushing the device over the pavement to be marked without interfering with the traffic to any considerable extent.

The preferred form of my invention is shown in the accompanying drawings in which Figure 1 represents a longitudinal section through my device taken substantially along line 1—1 of Figure 3, Figure 2 a side view of my device, Figure 3 an enlarged vertical cross-section through the same taken along the center line of the device, Figure 4 a detail view of a portion of a track used in my device and Figure 5 a detail side view of a modified form of a paint receptacle adapted to be substituted for the one shown in the principal form under certain conditions. While I have shown only the preferred form of the invention it should be understood that various changes or modifications may be made within the scope of the claims hereto attached without departing from the spirit of the invention.

My device is supported on two wheels (1) of rather large diameter, in the hubs (2) of which is supported an axle (3), bushings (4) serving as bearing members. Grease may be admitted to the bearings through grease cups (6). The wheels are provided with wide rims (7) and support on their axle the housing (8) comprising side members (9) designed to cover the operative portions of the device and transverse mem-

bers (11) connecting the side members. The latter are perforated centrally so that they may be slipped over the reduced ends of the axle and are held in place by sleeve nuts (12) threadedly engaging the said reduced ends while caps (13) adapted to be screwed on the sleeve nuts serve to keep out dust and other impurities.

On the top connecting member (11) is supported a receptacle (14) adapted to be filled with liquid paint, an inlet opening (16) being provided with a plug (17) for closing the same. A float (18) is preferably disposed within the tank having a stem (19) secured thereon which extends through the cap and indicates to the operator the paint level. A discharge pipe (20) communicates with the bottom of the receptacle and leads to within close proximity of the pavement to be marked, adapted to deliver the liquid paint in front of the rotary brush (21) rotatably supported in two hangers (22) suspended from the axle (3) and normally held in a vertical position by means of a handle (23) pivotally engaging the shaft (24) on which the brush rotates and resting with its upper end on one of the transverse connecting members (11) previously mentioned. A plurality of notches (26) are provided in the lower face of the handle adapted to engage the transverse member for holding the handle against longitudinal motion. To lift the brush out of engagement with the pavement surface it is only necessary to pull the handle upwardly and to engage the transverse member (11) with a lower notch.

Rotary motion is imparted to the brush by means of a chain drive from one of the wheel hubs, a cog wheel (28) fixed to the hub driving a transverse shaft (29) supported in one of the hangers (22) through a cog wheel (31) and a second cog wheel (32) on the shaft (29) being operatively connected, through a chain (33), with a cog wheel (34) on the shaft (24). The chain passes around an idler (36) supported on a pin (37) riding in a slot (38) in the hanger and forced away from the shaft (24) by a spring (39) which latter thus serves to hold the chain under tension while allowing the shaft (24) to ride downwardly in a vertical slot (41) in the hanger when the brush becomes smaller due to wear. The port area of the discharge pipe (20) is controlled by a suitable valve (42) adapted to be shut and opened by means of a rod (43) extend-

ing rearwardly and provided, at its extreme end, with a hand wheel (44).

To limit the lateral range of the brush and to provide a clean cut margin for the mark, I provide a link track (46) on either side of the brush, the tracks passing over and under the main wheels and rollers (47) supported on shafts (48) disposed in the front and rear ends of the housing. A fragmentary portion of the two tracks is shown in Figure 4 from which it will appear that each track consists of a plurality of flat plates (49) provided with marginal flanges (51) which latter are pivotally connected as shown at (52), in the drawing. When passing underneath the main wheels (1) they lie flat on the pavement surface and limit the range of the brush laterally so as to produce a mark with straight marginal lines. In case it is desired to provide periodical notices such as "40 Minutes" in the mark this may be accomplished by connecting two corresponding links of the two tracks by a special link (53) having said notice cut into the same. Since this link would travel with the tracks it would be necessary to provide a receptacle that would not interfere with the travel of the said link and for this purpose the receptacle (54) shown in Figure 5 might be substituted for that shown in the main drawing.

In the rear end of my device I provide a means for making terminal marks such as a large circular spot comprising a brush (56) supported on a vertical rod (57) pivoted in a frame (58) projecting from the rear end of the main housing. The brush may be held out of contact with the pavement surface by pressing on a foot pedal (59) pivotally supported in the frame as shown at (61) and engaging the rod between two collars (62). The upper face of that portion of the lever engaging the upper collar is shaped angular so as to hold the rod in an elevated position after the free end of the lever has been pressed down by the foot. To make a terminal mark the free end of the lever is lifted by striking the same with a foot whereupon the brush may be rotated by means of the crank handle (63).

Lateral angle irons (64) secured to the bottom of the housing tend to reinforce the same and brackets (66) are provided to prevent the device from tipping over sideways, and the whole device is pushed forward by means of handle (67).

I claim:

1. A pavement marker of the character described, comprising a housing having a paint receptacle supported therein, a pair of wheels, an axle connecting the same supporting the housing, hangers suspended from the axle having a rotary brush supported therebetween, means for transmit-

ting rotary motion to the brush from the axle, means for feeding paint on the pavement in front of the brush and means for laterally limiting the range of the brush, comprising a link track associated with each wheel and rollers mounted in front and in the rear of the wheels for guiding the track.

2. A pavement marker of the character described, comprising a housing having a paint receptacle supported therein, a pair of wheels, an axle connecting the same supporting the housing, hangers suspended from the axle having a rotary brush supported therebetween engaging the pavement surface, means for feeding paint on the pavement in front of the brush, a chain drive for transmitting rotary motion to the brush from the axle, and a handle pivotally engaging the brush support for swinging the brush from the pavement into an inactive position.

3. A pavement marker of the character described, comprising a housing having a paint receptacle supported therein, a pair of wheels, an axle connecting the same supporting the housing, hangers suspended from the axle having a rotary brush supported therebetween engaging the pavement surface, means for feeding paint on the pavement in front of the brush, a chain drive for transmitting rotary motion to the brush from the axle, a handle pivotally engaging the brush support for swinging the brush from the pavement into an inactive position and a cross-member on the housing adapted to engage a notch in the handle for supporting the brush in an inactive position.

4. A pavement marker of the character described, comprising a rotary brush, portable means for feeding liquid paint in front of the brush having means associated therewith for imparting rotary motion to the brush and means for laterally limiting the range of the brush.

5. A pavement marker of the character described, comprising a rotary brush, portable means for feeding liquid paint in front of the brush having means associated therewith for imparting rotary motion to the brush and a second brush rotatable on a vertical axis supported rearwardly of the first brush for making terminal marks.

6. A pavement marker of the character described, comprising a rotary brush, portable means for feeding liquid paint in front of the brush having means associated therewith for imparting rotary motion to the brush and a second brush rotatable on a vertical axis supported rearwardly of the first brush for making terminal marks, said second brush having a foot pedal connected therewith adapted to normally render the same inactive.

7. A pavement marker of the character described, comprising a rotary brush, portable means supporting the brush in engagement with the pavement surface having means associated therewith for feeding paint in front of the brush and means for laterally limiting the range of the brush so as to produce straight marginal lines.

8. A pavement marker of the character described, comprising a rotary brush, portable means supporting the brush in engagement with the pavement surface having means associated therewith for feeding paint in front of the brush and means for laterally limiting the range of the brush so as to produce straight marginal lines, with a second brush rotatable on a vertical axis

supported rearwardly of the first brush for producing circular marks.

9. A pavement marker of the character described, comprising a rotary brush, portable means supporting the brush in engagement with the pavement surface having means associated therewith for feeding paint in front of the brush, means for laterally limiting the range of the brush comprising a link track associated with each wheel and rollers mounted in front and in the rear of the wheels for guiding the track and a plate supported between two links of the tracks having marks cut therein adapted to periodically pass under the brush for reproducing said marks.

JAMES T. NARBETT.
